LAMP SUPPORT.

APPLICATION FILED SEPT. 21, 1917.

Patented Oct. 22, 1918.

2 SHEETS—SHEET 2.

Inventor:
William J. Carlin,
by Walter E. Lombard, Atty.

UNITED STATES PATENT OFFICE.

WILLIAM J. CARLIN, OF ROXBURY, MASSACHUSETTS.

LAMP-SUPPORT.

1,282,676.

Specification of Letters Patent. Patented Oct. 22, 1918.

Application filed September 21, 1917. Serial No. 193,201.

To all whom it may concern:

Be it known that I, WILLIAM J. CARLIN, a citizen of the United States of America, and a resident of Roxbury, in the county of 5 Suffolk and Commonwealth of Massachusetts, have invented certain new and useful Improvements in Lamp-Supports, of which the following is a specification.

This invention relates to supports for electric lamps and has for its object the production of a support of this character which is so adjustable that the rays from the lamp may be thrown in every possible direction.

The invention consists of a tubular section 15 mounted on a suitable base and having hinged to its opposite end an extension rod provided at one end with a pair of clamps adapted to support the lamp socket.

The invention further consists in so 20 mounting the socket carrying rod on the tubular section that said rod may be telescoped into said tubular section when desired.

The invention further consists in certain 25 novel features of construction and arrangement of parts which will be fully understood by reference to the description of the drawings and to the claims hereinafter given.

For the purpose of illustrating the invention one preferred form thereof is illustrated in the drawings, this form having been found to give satisfactory and reliable results, although it is to be understood that the various instrumentalities of which the invention 35 consists can be variously arranged and organized, and that the invention is not limited to the precise arrangement and organization of these instrumentalities as herein shown and described.

40 Of the drawings:

Figure 1 represents an elevation of the upper portion of a lamp support embodying the principles of the present invention.

Fig. 2 represents an elevation of the support with the supporting rod telescoped into the tubular section.

Fig. 3 represents a sectional detail on line 3-3 on Fig. 1, and Fig. 4 represents a section on line 4-4 on Fig. 2.

50 Similar characters designate like parts throughout the several figures of the drawings.

In the drawings 10 is a ball shaped member or center-piece having a plurality of 55 radial legs 11 extending therefrom and forming a base.

The upper part of the ball 10 is provided with a hub 12 into which is threaded the standard or tubular section 13, having a clear straight passage therethrough and the upper end of which has threaded thereto a nut 14.

Surrounding the tubular section 13 and beneath the nut 14 is a sleeve 15 provided with a laterally extending wing or projection 16, the outer end of which has a disk-like portion 17, through the center of which is an opening to receive the pivot bolt 18.

Straddling the disk portion 17 is a bifurcated member 19 provided with disk portions, having alined openings extending therethrough to receive the pivot bolt 18, one end of which is threaded to the hub 20 formed upon one of the disk portions of the bifurcated member 19, while the opposite end thereof is provided with a head 21.

It is obvious that by turning the pivot bolt 18 the two disk portions of the bifurcated member 19 may be brought into firm contact with the outer faces of the disk 17 interposed between said disk portions and cause sufficient friction thereon to lock the member 19 to the sleeve 16 in adjusted position.

85 The member 19 is provided with a tubular hub 22 in which is mounted the cylindrical extension rod 23. This rod or extension 23 may be adjusted endwise in the hub 22 and clamped in adjusted position by means of 90 the clamp 24 threaded to the boss 25 extending from the hub 22.

The axis of the pivot bolt 18 is equi-distant from the axis of the hub 22 and the axis of the tubular section 13, so that when the bifurcated member 19 is moved into the position indicated in Fig. 2 of the drawings, the axes of the rod or extension 23 and the tubular section 13 will be in alinement. The diameter of the rod or extension 23 is 100 less than the interior diameter of the tubular section 13 thereby making it possible to telescope the rod or extension 23 into the tubular section 13 when the hinged device 16, 19 is in the position indicated in Fig. 2. 105

The sleeve 15 is provided with a laterally extending boss 26 in which is threaded a clamping member 27 by which the sleeve 15 may be locked in adjusted position on the tubular section 13. It is obvious that by 110 unclamping the member 27, the sleeve 15 is free to turn about the axis of the tubular

section 13 and then again be locked in adjusted position by means of said clamping member 27.

By loosening the clamp 24 and moving 5 the extension rod 23 endwise through the tubular hub 22, said rod may be entirely removed from the tubular section 13 and then the member 19 may be moved into any desired position relatively to sleeve 15 and 10 clamped in adjusted position by means of the pivot bolt 18.

Two such positions are indicated in Fig. 1 of the drawings, one in full lines and the other in dotted lines.

15 Threaded to the outer end of rod 23 is a nut 28 having the threaded projection 29 extending therefrom in axial alinement with the extension rod 23. Threaded to the projection 29 is a ball 30 positioned between 20 two swivel members 31 preferably made of Babbitt metal and having reduced ends positioned in openings 32 in the lower ends of the socket-clamps 33. The upper ends 34 of said socket-clamps are curved with their 25 inner faces adapted to impinge upon a lamp socket 35 of any well known construction.

The socket-clamps 33 are connected together by means of the clamping bolt 36, one end of which is provided with a slotted 30 head for turning said bolt, said head bearing against one socket-clamp 33, while the opposite end is threaded to a nut bearing against the outer face of the other socket-clamp 33 as indicated in Fig. 4 of the drawings.

35 When the clamping bolt 36 is adjusted, it not only clamps the socket-clamps 33 upon the socket 35, but also clamps the swivels 31 upon the ball 30, thus positioning the 40 socket-clamps 33 at any desired angle to the axis of the projection 29 as, for instance, in the positions as shown in Figs. 1 and 2 in the drawings.

It is obvious that by the adjustment of 45 the clamping bolt 36, the socket 35 may be easily removed from the socket clamps 33 and it is also self evident that by a slight turn of the clamping bolt 36, the friction of 50 these swivels and the inner faces of the socket-clamps 33, may be relieved sufficiently to permit the socket-clamps to be moved into a new position and locked in said adjusted position by said clamping bolt 36.

55 The lamp-supporting-extension rod 23 may be adjusted endwise or longitudinally in the hub 22 to move the socket 35 to any desired distance from said hub and then said extension rod may be clamped in adjusted position by means of clamp 24. The bifurcated member may be moved into any desired angle relatively to the sleeve 15 and clamped in adjusted position by the pivot bolt 18. This whole hinged device, 15, 16, 19 60 65 may be swung about the axis of the tubular

section 13 and locked in adjusted position by means of the clamping member 27.

A portion of the nut 14 on the upper end 70 of the tubular section 13 projects into the lateral slot 37 in the ring 16 thereby preventing the sleeve 15 from being displaced from its normal position as indicated in the drawings.

This makes a very desirable lamp support particularly adapted for garage work, as by 75 means of the structure shown the various parts may be quickly adjusted so that the light may be thrown up under machines, or may be thrown down, upon any of the working parts of the machine. In fact the device may be adjusted so as to throw light 80 wherever it may be most needed.

One great advantage of the device is, that whenever it is found unnecessary to project 85 the light at some distance from the vertical standard or tubular section 13, the extension rod 23 may be telescoped into the said tubular section 13 as is indicated in Fig. 2, thereby causing it to occupy less space.

It is believed that the operation of the device and its many advantages will be thoroughly understood without any further description.

Having thus described my invention, I 90 claim:

1. In a device of the class described, a base; a tubular section connected at one end thereto; a hinged device having one part thereof secured to the opposite end of said tubular section; a lamp-supporting-extension adjustable endwise in the other part of 95 said hinged device and one end of which is adapted to be positioned in said tubular section; and a lamp socket mounted on the other end of said adjustable extension.

2. In a device of the class described, a base; a tubular section connected to one end thereto and having a clear straight passage therethrough; a sleeve secured to the opposite end of said tubular section and provided with a lateral flat-sided wing having a transverse opening; a pivot bolt in said opening; a member mounted on said pivot bolt and provided with a tubular hub, said member being adapted to be moved about said pivot 100 to bring the axis of said hub in alinement with the axis of said tubular section; a lamp-supporting-extension of less diameter than said passage through the tubular section, adjustably mounted in said tubular hub and one end of which is adapted to be positioned in said tubular section; and a lamp socket mounted on the other end of said extension.

3. In a device of the class described, a base; a tubular section connected at one 105 end thereto and having a clear straight passage therethrough; a sleeve secured to the opposite end of said tubular section and provided with a lateral flat-sided wing having a transverse opening; a pivot bolt in said 110

opening; a member movable about said pivot bolt and provided with a tubular hub in the same vertical plane as said tubular section, the axes of said tubular hub and said tubular section being equi-distant from said pivot bolt thereby permitting said axes to be brought into alinement; a lamp-supporting extension of less diameter than said passage through the tubular section and adjustable 10 endwise in said tubular hub; and a lamp socket mounted on the outer end of said extension.

4. In a device of the class described, a base; a tubular section connected at one end thereto and having a clear straight passage therethrough; a sleeve adjustable about the axis of the opposite end of said tubular section; a clamping member therefor; a tubular hub pivoted to said sleeve and adapted to 20 be moved into alinement with said tubular section; an extension rod of less diameter than the passage in said tubular section and adjustable endwise in said tubular hub; means for clamping said rod to said hub; 25 and a lamp socket mounted on the outer end of said rod.

5. In a device of the class described, a base; a tubular section connected at one end thereto and having a clear straight passage 30 therethrough; a sleeve adjustably mounted on the opposite end of said tubular section and provided with a lateral wing; a clamping member therefor; a tubular hub provided with a forked portion straddling said 35 lateral wing; a pivot bolt extending through said forked portion and wing equi-distant from the axes of said hub and section and including means for clamping said hub and sleeve in adjusted position relatively to each 40 other; an extension rod of less diameter than the passage in said tubular section and adjustable endwise in said tubular hub; and a lamp socket on the outer end of said rod.

6. In a device of the class described, a

base; a tubular section connected at one end 45 thereto; a nut threaded to the opposite end of said tubular section; a hinged device mounted on said tubular section, one part of which is provided with a transverse slot in which a portion of said nut is positioned, 50 while the other part is provided with a tubular hub; a rod adjustable endwise in said tubular hub; and a lamp socket mounted on the outer end of said adjustable rod.

7. In a device of the class described, a base; a tubular section connected at one end thereto; a sleeve adjustable about the opposite end of said tubular section and provided with a lateral wing; a tubular hub; means 60 for clamping said hub to said lateral wing in adjusted position; an extension adjustable endwise in said hub; a ball secured to the outer end thereof; a lamp socket; and two socket clamps adapted to be clamped to 65 said ball and provided with curved ends adapted to be clamped to said socket.

8. In a device of the class described, a base; a tubular section connected at one end thereto; a sleeve adjustable about the opposite end of said tubular section and provided with a lateral wing; a tubular hub; means 70 for clamping said hub to said wing in adjusted position; an extension adjustable endwise in said hub; a ball secured to the outer 75 end thereof; swivel members on said ball; two socket-clamps each provided with an opening in which a swivel member is positioned; a lamp socket; and a clamping bolt connecting said socket clamps between said 80 swivel members and the socket-holding ends of said socket-clamps.

Signed by me at 4 Post Office Sq., Boston, Mass. this 20th day of September 1917.
